UNITED STATES PATENT OFFICE.

EDWARD C. LUEDTKE, OF LAPORTE, INDIANA.

MEDICINE DROPPER.

1,412,948.

Specification of Letters Patent. Patented Apr. 18, 1922.

Application filed December 20, 1920. Serial No. 431,816.

To all whom it may concern:

Be it known that I, EDWARD C. LUEDTKE, a citizen of the United States, residing at Laporte, in the county of Laporte and State 5 of Indiana, have invented a certain new and useful Improvement in Medicine Droppers, of which the following is a specification.

This invention relates to a medicine dropper, and is designed for use where it 10 is necessary or desirable to discharge fluids from their container in small quantities as for example in drops. It is particularly adapted for use as an eye dropper. One object of this invention is to produce an eye 15 dropper which may be easily used and which will not accidentally discharge too great a quantity of the liquid contained in it at any given time.

This invention is illustrated in the accompanying drawings, wherein,

Figure 1 is a side elevation of the device complete on a magnified scale;

Figure 2 is a vertical section through the device much enlarged.

Like parts are indicated by like characters throughout.

A is a supporting casing which may be made of metal, fibre or other suitable material. It is narrowed at its bottom as at A' 30 and has the small opening A². It is closed at the top by a cap A³ which may be screw threaded upon the body portion A or secured thereon in any suitable manner. The cap A³ is perforated at A⁴ for the admission of the plunger A⁵. The plunger A⁵ has at its upper end the enlarged portion A⁶ and at its lower end the cup shaped enlargement A⁷ which contacts and supports the liquid container. A⁸ is a slot in the side of 35 the casing through which the operator may see the quantity of liquid which is in the container.

B is a liquid container which may be of any suitable form. As here illustrated, it 45 is in the form of a bottle having the narrowed portion B' toward its lower end and terminates in the perforated point B². The point B² is normally closed by a small rubber cap B³ although, it might of course, be 50 closed in any other suitable manner. C is a ring adapted to surround the lower portion of the bottle and to support it. Fastened to the ring C are a plurality of springs C'; these are fastened at the points C' C² 55 and may be secured there in any suitable

manner. In the form here shown they are mounted on rivets which are positioned in the side of the casing A. The tension of the springs C' is sufficient to hold the bottle up against the boss D on the inside of the cap A³.

Although I have shown in my invention an operative structure, still it will be obvious that many changes both in form, shape and arrangement of parts may be 65 made without departing from the spirit of my invention and I wish therefore that my showing be taken as in a sense diagrammatic.

The use and operation of this invention 70 are as follows:

The bottle is normally held up against the closure of the casing by means of the springs. When it is desired to use the bottle the rubber cap is removed and the operator 75 takes the dropper in his hand and places his thumb upon the bottle and the upper end of the plunger. He then depresses the plunger and thus, of course, causes the bottle to move downward; when the bottle 80 strikes the contracted portion of the casing, its movement is arrested but the liquid within the bottle, by reason of its inertia tends to continue its movement and thus a quantity of liquid, for example, a drop, is forced 85 out of the opening of the bottle. The pressure is then removed from the bottom on the plunger and the bottle is restored to its original position. Whereupon, the operation 90 may be repeated indefinitely. The quantity of liquid discharged at any given operation, is, of course, varied by the size of the device and in particularly by the size of the opening

95 I claim—

1. In a liquid dispenser a casing, an opening in said casing, a liquid container mounted and movably held within said casing, means adapted to cause said container to move partially through said perforation. 100

2. In a liquid dispenser a casing, an opening in said casing, a liquid container mounted and movably held within said casing, means adapted to cause said container to move partially through said perforation for 105 abruptly stopping said motion.

3. In a liquid dispenser a liquid container supporting means surrounding said container, said container yieldingly held within said supporting means, means for moving 110

said container with relation to said supporting means and means for abruptly stopping the motion of said container.

4. In a liquid dispenser a casing perforated at one end, a liquid container mounted and yieldingly held within said casing, means adapted to cause said container to move partially through said perforation, said means including a plunger, and means 10 for stopping said motion.

5. In a liquid dispenser a casing perforated at one end, a liquid container mounted and yieldingly held within said casing, means adapted to cause said container to 15 move partially through said perforation, said means including a plunger and means for stopping said motion, and a longitudinal slit in said casing.

6. In a liquid dispenser, a casing, perforated at one end and having a removable closure at the other, a liquid container

mounted within said casing, spring supporting means adapted normally to hold said container against movement, a plunger adapted to cause movement of said container in opposition to said spring means and means for abruptly stopping said motion. 25

7. In a liquid dispenser, a casing perforated at one end and having a removable closure at the other, a liquid container mounted within said casing, spring supporting means adapted normally to hold said container against movement, a plunger adapted to cause movement of said container 30 in opposition to said spring means and means for abruptly stopping said motion, and a longitudinal slit in said casing. 35

Signed at Laporte, county of Laporte and State of Indiana, this 17th day of December, 1920. 40

EDWARD C. LUEDTKE.
